(57) **CLAIM**

The ornamental design for a facial cleaning brush, as shown and described.

DESCRIPTION

FIG. 1 is a top, rear and right side perspective view of a facial cleaning brush showing my new design;

FIG. 2 is bottom, front and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of portion 9 shown in FIG. 1. The long-short-long dashed lines showing the bounds of the detail view (FIG. 9) and the portion of FIG. 1 from which it was extracted, form no part of the claimed design.
